Walton Harrison
his ATTORNEY

UNITED STATES PATENT OFFICE.

MALVIN LICHTER, OF NEW YORK, N. Y., ASSIGNOR TO HIMSELF AND LOUIS JACOBS, PARTNERS, TRADING AS STICKLESS FAN COMPANY, OF NEW YORK, N. Y.

DELIVERY CHUTE FOR USE WITH CUTTING DIES.

Application filed August 25, 1922. Serial No. 584,177.

My invention relates to delivery chutes for use with cutting dies, my more particular purpose being to facilitate the delivery of the articles cut out by the dies in such 5 manner as to prevent the articles from jamming or becoming unduly crowded.

My invention further contemplates the arrangement of the delivery mechanism so that the cutting operation of the dies, and 10 the delivery of the finished article cut thereby, require only a minimum of space.

In addition my invention comprehends an arrangement of the delivery mechanism so that practically all portions of the latter are 15 accessible to the operator at all times, and even while the mechanism is in operation.

More particularly stated, I seek to produce a delivery mechanism especially adapted for use in connection with a pair 20 of cutting dies of the type used for making cardboard fans and similar articles, the mechanism being so distributed and arranged in position that the cutting dies may work continuously, and the articles cut out 25 by the dies are to all intents and purposes automatically assembled and delivered from the cutting dies, the power for this purpose being supplied by the normal working or cutting movement of one of the die 30 members relatively to the other.

Reference is made to the accompanying drawing forming a part of this specification, and in which like reference characters indicate like parts throughout the several figures.

Figure 1 is a substantially central vertical section through a pair of cutting dies equipped with my device.

Figure 2 is a section on the line 2—2 of Figure 1, looking in the direction indicated by the arrows.

Figure 3 is a section on the line 3—3 of Figure 1, looking in the direction indicated by the arrows.

A strip of cardboard is shown at 4, and 45 is used in making the body portion of the fans to be cut, as hereinafter described.

The cardboard strip 4 is preferably of great length, and is fed endwise in the manner well known in this art. This cardboard 50 strip carries a number of substantially V-shaped handle members 5 and 6, arranged in pairs, the members of each pair being located upon opposite faces of the cardboard strip 4 and adhering to the cardboard strip 55 by aid of an adhesive. For purposes of my

invention, therefore, the cardboard strip 4 may be considered as a continuous strip having the form indicated in Figures 1 and 2, and fed continuously endwise, with a step by step movement, in the manner well 60 understood in this art.

A portion of the strip 4 to be cut out by the dies is shown at 7, and at 8 is shown a similar portion as it is cut from the strip 65 and thus converted into a fan.

The two members of the cutting die are shown at 9 and 10, and constitute the positive and negative members of the die. The lower die member 10 is the negative member of the die and is secured upon a table, 70 shown fragmentarily at 11 and provided with an opening 12, through which the finished fans pass downwardly, as indicated in Figure 1. The lower die member 10 carries a number of guide pins 13 which extend upwardly, through holes in the die member 9. The upper die member 9 is mounted to slide vertically upon the guide pins 13, and is thus always strictly parallel 75 with the lower die member 10.

The upper die member 9 is provided with a cutting edge 14, and the lower die member 10 is provided with a mating cutting edge 15. These cutting edges are so formed that in severing the portion 7 from the 80 strip 4, such portion is given the form indicated at 8 in Figure 2; or in other words the dies are properly formed to give the required shape to the finished fan.

For actuating the upper die member 9 90 it is provided with a pin 16, and journaled upon this pin is a link 17, connected with and operated by an eccentric 18, this eccentric being mounted upon a revoluble shaft 19, through which power is supplied. 95 Thus the upper die member 9 is caused to reciprocate relatively to the die member 10, so as to continuously cut out fans 8, one at a time.

By means of bolts 20 the die member 10 100 is held rigidly in position, so that the die mechanism as a unit is fixed relatively to the supporting table 11.

Each fan 8, after being severed from the cardboard strip 4 as above described, has 105 the form shown in Figure 3. It is provided with a hole 22, to be used by the operator as a thumb hole, and is further provided with a pair of concave edges 23 having but little curvature, and a pair of other con- 110

cave edges 24, having somewhat greater curvature, as may be understood from Figure 3. The concave edges 23 and 24 are used for supporting the fan during its delivery from the cutting die, as may be understood from Figure 3.

To facilitate the delivery of the fans, I provide a pair of metallic rails 25, each curved in the general direction of its length, 10 as indicated in Figures 1 and 2, the general curvature of each of the two rails approximating in this instance a parabola.

Disposed adjacent the rails 25 are a pair of rails 26.

15 The rails 25 and 26 are in this instance each circular in cross section, the rails 26 each being of smaller diameter than either of the rails 25, and located a little lower than the latter, but in close proximity thereto.

20 The rails 25 and 26 are so proportioned and arranged that each fan 8 supported by them as indicated in Figure 3 rests upon them in the manner shown, the concave edges 23 resting upon the rails 25 and the concave edges 24 resting upon the rails 26. Thus each fan has a good bearing upon the rails, and is supported quite firmly thereupon, by its own weight.

25 The rails 25 are supported by pins 27, extending through sideboards 28 and having portions 29, threaded and of reduced diameter, which extend through the sideboards and are engaged by nuts 30, as shown more particularly in Figure 3. The rails 26 are supported upon pins 31, which extend laterally inward from the sideboards.

30 The sideboards 28 and the various parts carried thereby are supported upon legs 32 and 33, the latter being secured to a floor 34 or analogous supporting surface by means of bolts 35.

40 I provide a pair of brackets one of which is shown at 36, for supporting the portions of the sideboards 28 in immediate proximity to the die number 10.

45 The guide rails 25 and 26 and parts immediately associated therewith collectively constitute a chute for supporting and guiding the fans 8, as the latter are cut one at a time as above described and thus fed into the chute in a manner practically automatic. It will be noted that in consequence of the location of the cardboard handle members 5 and 6 carried by and forming a part of each fan, the fan as a whole is practically rendered thicker at one point than at another. That is to say, broadly speaking, the portion of the fan serving as a handle and shown at the bottom of Figure 3 is considerably thicker than the upper portion of the fan according to this figure. Such being the case, when a number of the fans are crowded together as shown in Figure 1, so that the relative thicknesses of the fans is in a sense cumulative, the entire

group of fans, considered as a continuously moving column, has a tendency to bend rather sharply. It is because of this tendency that I curve the guide wheels 25 and 26, as above described.

70 By giving to the guide rails the form shown in the drawing and above described, the column of fans practically crawls from the cutting dies, first downwardly and then obliquely upward, as may be understood from Figure 1. Each individual fan thus follows a general path of travel having a form approximating that of a parabola, and the body of fans as a unit has at any particular moment the form of a column, bent 80 substantially into a form corresponding to the path of travel of each fan.

75 It will be noted that the guide rails 25 and 26 are each substantially straight in the portion to the right thereof according to Figure 1. In other words the guide rails are straight in that portion of the chute from which the fans are actually removed by hand. By this arrangement the upper or blade portions of the fans are spaced 90 apart slightly, as indicated in Figure 2, so that the operator can readily slip his fingers in between any two fans which are consecutive and located near the end of the column. By doing this with one hand so as to separate a bunch of fans from the general column, and by placing his other hand underneath the bunch of fans thus separated, he simply slides or lifts the bunch off the guide rails and thus effects the removal of the 100 fans.

85 It will be noted from Figure 2 that the general axis of each fan as cut from the cardboard step 4 is oblique relatively to the length of the cardboard strip. This is for the purpose of avoiding waste in cutting the cardboard. Therefore I so arrange the various parts of my device that the chute, as a whole, occupies a general vertical plane which is oblique to the length of the strip 4 95 and to the general direction of travel thereof. This arrangement renders the movement of each fan comparatively simple, and causes the column of finished fans to leave the cutting dies in such direction of travel that, seen from above, the column of fans is oblique to the general direction of the length of the strip 4. By this arrangement the column of fans occupies such position relatively to the cutting dies as to facilitate access to the cutting dies and parts immediately associated therewith. Thus the operator can stand quite close to the cutting dies and directly in line with the length of the strip 4 and with the direction of travel thereof, for the purpose of inspecting the cutting dies, and removing shreds of cardboard formed by the cutting of the fans. In other words, practically speaking, the chute guides the column of fans out under 120 130

a corner of the table, so to speak, thus rendering it easy for the operator to come up to the end or to one side of the table, and into close proximity to the cutting dies.

5 I do not limit myself to the precise mechanism shown, as variations may be made therein without departing from my invention, the scope of which is commensurate with my claims.

10 I claim:—

1. The combination, with a pair of cutting dies one of which is movable and the other stationary, of a chute connected with the stationary die and comprising a number 15 of guide rails each having the form of a rod, said rails being arranged in pairs, the rails of each pair being spaced apart, the rails of one pair being spaced further apart than the rails of another pair, all of said 20 rails being together so positioned relatively to the stationary die as to receive and deliver the articles cut by the dies.

2. In a device of the character described the combination, with a stationary die provided with an opening and a movable die 25 provided with a cutting portion mating said

opening and adapted to extend thereinto, of means for guiding between said dies a longitudinal strip of stock material traveling step by step in the direction of its length, a chute communicating with said opening and arranged to receive therefrom the articles cut by the dies, said chute being curved in a substantially vertical plane for the purpose of delivering said articles to a predetermined point, said vertical plane of said chute extending obliquely to the direction of travel of said strip of stock material.

3. In a device of the character described the combination, with a stationary cutting die provided with an opening and a movable cutting die provided with a cutting portion mating said opening and adapted to extend thereinto, of means for feeding a strip of stock material in the direction of its own 40 length to said dies along a straight path, and a chute communicating with said opening and arranged to receive therefrom the articles cut out by the dies, said chute extending in a plane oblique to the length of 45 said strip of stock material.

MALVIN LICHTER.
